7 Claims. (Cl. 103—52)

The present invention relates to gas pressure-operated pumps and systems for raising liquids from oil wells and pertains particularly to gas-lift pumps having, and to systems using, a plunger which is raised to the surface by means of gas pressure and which carries upwards a load of well fluid.

In gas-lift pumps the well liquid is allowed to accumulate in a tubing or eduction tube, then gas is introduced at the bottom of the tube and the liquid is forced to the surface by the gas. By then releasing the gas pressure and repeating the cycle well liquids may be raised to the surface. However, with this system the consumption of gas, that is the gas-oil ratio, is uneconomically high for many wells and, consequently, freely moving plungers have been used between the load of well fluid and the driving gas to prevent part of the rising liquid from adhering to the wall of the tubing or eduction tube and flowing back or even, in the event of the velocity of the gas being too low, from falling back directly in free drops, which would result in too high a gas-oil ratio.

Generally, with the known "plunger lift" systems only the head or upper portion of liquid above the plunger in its lowermost position is raised with each stroke, but so that gas consumption be low, a large load of liquid should be raised per cycle. Therefore, according to the known systems, the liquid level in, and consequently also outside the tubing is allowed to rise considerably in order to compensate for the limited diameter of the tubing. Although decreased gas consumption is thereby obtained, these systems have the disadvantage of a high liquid level, which naturally means a high back pressure on the producing layer and which adversely affects the producing capacity of that layer.

It is, therefore, an object of the present invention to provide an improved well pumping system, whereby large loads of well liquid can be raised with both low gas consumption and low liquid level in the well.

It is another object of the present invention to provide an improved well pump of the gas-powered type.

It is a further object of the present invention to provide an improved well pump having a displacement chamber and an arrangement whereby said chamber is substantially emptied of the accumulated well fluid in each cycle.

Further objects and advantages will be apparent from the following description taken in reference to the drawings, wherein:

Figure 1 is a vertical sectional view of a well showing schematically a preferred embodiment of the present well pump.

Figure 2 is a schematic sectional view of a modification of the liquid-accumulating portion of the present device.

Figure 3 is a schematic sectional view of another modification of the liquid-accumulating portion of the improved well pump.

Figure 4 is a schematic sectional view of still another modification of the liquid-accumulating portion.

Figure 5 is a schematic sectional view of another modification of the liquid-accumulating portion.

Figure 6 is a schematic sectional view of a further modification of the liquid-accumulating portion.

Figure 7 is a schematic sectional view of another modification of the liquid-accumulating portion.

Figure 8 is a schematic sectional view of still another modification of the liquid-accumulating portion.

Figure 9 is a schematic sectional view of a further modification of the liquid-accumulating portion.

According to the system of the present invention fluids from the producing formation penetrated by a well are allowed to pass into an accumulating space having a relatively large diameter and provided with means to prevent fluid flow in the reverse direction and with an eduction tube having a relatively small diameter and extending to the well head and a freely moving plunger within said tube. During the pumping cycle, when the plunger has reached its lowermost position in the eduction tube, a load of liquid is introduced into the space above the said plunger, with the aid of gas pressure. Pressure is then allowed to build up in the space below the plunger in the eduction tube, the plunger thus being lifted, together with its load of liquid, to the well head, where the liquid load is discharged. Thus, by applying gas pressure, the contents of a relatively short vertical interval of the borehole or, for instance, of a liquid-accumulating or gas displacement chamber, can be made to form a column of liquid of considerable height in the comparatively narrow eduction or lift tube, so that the gas-oil ratio can be much lower than would be possible with previous gas displacement systems, while at the same time excessive back pressure on the producing layer is avoided.

In well pumps capable of carrying out the above mode of operation it is preferable to provide automatic means for controlling the pressure difference between top and bottom side of the plunger in order to prevent the plunger from being lifted until almost all the liquid from the accumulating space has passed into the space in the lift tube above the plunger. Consequently in the improved well pumps of the present invention automatic means are provided for alternately directing the flow of fluid into the space in the lift tube either above or below the plunger

in response to a drop in liquid level or to cessation of the flow of liquid into the space above the plunger.

Referring to Figure 1 of the drawings, a borehole 1 contains a well casing 2 having the lower section thereof perforated or slotted with holes 3, as in a screen liner. An inner tubular casing 4 extends downward into the borehole within the well casing 2 and terminates in an accumulating or displacement chamber 5 of enlarged diameter. In the lower portion of the chamber 5 is a non-return valve comprising, for example, a valve opening and seat 6 and a ball valve 7, which permits well liquid to flow into the accumulating chamber 5, but prevents liquid from flowing from said chamber. The ball valve 7 is maintained in proper relation to its seat 6 by a valve cage 1a.

Within the casing 4 and depending into the chamber 5 is a tubing or lift tube 8, the annular space 9 between the casing 4 and the tubing 8 forming a conduit for pressure gas. Freely movable within the tubing 8 is a plunger or lift piston 10, which rests near the bottom of the tubing when in the stationary phase of its operation. At a point above the stationary position of the plunger 10 the tubing 8 is provided with lateral inlets or inlet ports 11 which permit accumulated liquid in the chamber 5 to enter the eduction tube 8. Carried in the lowermost portion of the tubing 8 and opening underneath the plunger 10 in its rested position is a gas inlet and valve seat 12, which is normally closed by a valve 13, which is carried by a horizontal member 14 projecting beyond the width of the tubing 8. A coil spring 15 or other resilient means, spaced between the member 14 and the bottom of the chamber 5, or other suitable support, normally holds the valve 13 against the valve seat 12.

Surrounding the tubing 8 is a float 16, preferably comprising a tubular section having an axial bore 17 and constructed so as to have a specific gravity less than oil well liquids. For example, the float 16 may be of a material such as wood (as shown) or may be of a hollow metal or other suitable construction. The diameter of the bore 17 is preferably somewhat larger than the outside diameter of the tubing 8, so that, when the float 16 is in a position about the tubing 8 at the level of the inlets 11, the bore 17 of the float 16 does not fit closely enough to seal the inlets 11, but forms a passage to allow restricted flow of liquid into the inlet ports 11.

In operation of the well pump of the present invention the liquid entering the borehole 1 from producing formations penetrated thereby passes through the holes 3 of the casing 2 and accumulates in the chamber 5, the ball valve 7 rising from its seat 6 to allow liquid flow. As the liquid rises in the chamber 5 and carries the float 16 upward, the inlet ports 11 are exposed, allowing liquid to enter the tubing 8 above the lift piston 10 in stationary position at the bottom of the tube 8. Gas pressure is then applied to the surface of the liquid in chamber 5 through the gas supply line 19 and the annular space 9 between the casing 4 and tubing 8. The pressure within the chamber rises quickly above the pressure outside the chamber and the ball valve 7 is thereby closed, thus preventing high pressures from being imposed upon the producing formations, which would lead to decreased production. The liquid in the chamber 5 is forced by the gas pressure into and upwards in the eduction tube 8 through ports 11. As the liquid level in the chamber is thereby lowered, the float 16 descends downward

about the tubing 8 until it rests on the projecting member 14, the load thereon increasing until the valve 13 is forced away from its seat 12 by the weight of the float 16 against the pressure of the spring 15. The gas pressure thus being automatically applied through the valve opening to this space underneath the plunger 10 in the lift tube 8, the plunger or lift piston travels upwards towards the surface, carrying the load of well liquid above it. At the well head the plunger 10 discharges by suitable means its load of liquid into a discharge pipe 18.

After the load of liquid is discharged, the gas pressure to the chamber 5 and thence to the tubing 8 is released and the plunger 10 falls to the bottom of the tube 8 as liquid accumulation within the chamber starts again. The cycle is then repeated at a rate depending on the size of the borehole, the apparatus, flow of liquid from the formations, etc.

To make the plunger 10 fall gradually on its return to the bottom, the diameter thereof may be slightly smaller than the inside diameter of the lift tube 8 or a small hole may be provided in the plunger bottom, or any other suitable means or plunger construction may be used. Likewise, for the same purpose the lower end of the tubing 8 may be provided with an outwardly opening non-return valve.

In a modification as shown in Figure 2, instead of a float and a normally closed valve, the lower end of the tubing 8 and an opening 20 therein is connected to an upwardly directed pipe 21, having a valve seat 22 and a shoulder 23 surrounding said valve seat. Fastened to the shoulder 23 is a relatively weak coil spring 24, supporting above it a horizontal plate member 25 to which a valve 26 is attached by means of rod 27, said spring 24 normally holding the valve 26 away from its seat 22. Vertical rods 28, acting as guides for plate 25 in its vertical movement, are affixed to the shoulder 23. The parts are arranged so that the plate 25 is always higher than the inlet ports 11 and is so spaced near to the tubing 8 that the liquid flowing into the inlets 11 must first pass around the plate 25.

In the operation of this modification gas pressure is likewise applied to the accumulated liquid in the chamber 5, forcing the liquid to pass into the lift tube 8 through inlets 11. The flow of liquid into the inlets 11 passing around the plate 25 drags the plate downwards, which brings the valve 26 into contact with the valve seat 22. The passage through the upwardly directed pipe 21 is thereby closed until substantially all the liquid above the plate 25 has been forced up into the tube 8 through the openings 11. As the liquid level falls below the plate 25, the dragging force of the flowing liquid on the plate 25 is removed and the valve 26 is forced open by the action of the spring 24. Gas then rushing into the pipe 21 forces the lift piston 10 with its load of liquid to the well head, where the liquid is discharged, and the cycle is repeated.

According to another embodiment, as shown in Figure 3, the valve 13, which engages the opening and valve seat 12 in the bottom of the tubing 8, is carried by a float 30, so that the valve 13 is in closed position when the liquid level in the chamber 5 is high and is in open position when the level is low. The lateral openings or inlets 11 are provided with tubular conduits 31, which extend downward and open near the bottom of the chamber 5 or open at a point at or below the level of the bottom of the float 30 when in its uppermost position. Guides 32 are provided to

insure that the float 30 is axially aligned, so that the valve 13 correctly engages its seat 12; or the tubular conduits 31, when three or more are used, may be arranged to provide a sliding fit about the float 30 and thereby guide the valve 13 into its proper position.

It can readily be seen that in this modification the valve 13 is kept closed by the buoyant force of float 30 during the period when liquid is being forced into the tubing 8 through conduits 31, and opens when the liquid level falls to such an extent as no longer to force the float 30 and valve 13 up against the valve seat 12. The rest of the operation is similar to that of the first-described embodiment.

A slight variation of the last-described modification is shown in Figure 4, wherein the tubular conduits 31 from the lateral openings or inlets 11 are replaced by a tube or tubular apron or jacket 40, which surrounds the lower part of the tubing 8 and the float 30 and which is narrowed at the top and fastened by the narrowed portion circumferentially to the tubing 8 at a point above the inlets 11. In this construction the float 30 holds the valve 13 in closed position by not only its buoyancy, but also due to the driving force of the upwardly moving liquid imparting a dragging action on the float 30.

This last-described embodiment may be still further varied to obtain some other special advantages. As shown in Figure 5, the tube or tubular apron or jacket 40 is narrowed in the lower portion below the float and extended downwards as a tubing 50. In this modification the apron or jacket 40 with the working parts therein may be located in the upper part of the accumulating or displacement chamber 5. The lower part of the chamber thus remains available for accumulation of liquid and the bottom of this chamber, together with the standing valve 7, is cleaned, or at least more nearly emptied completely, during each cycle, by the liquid which under gas pressure is passing along on its way upward.

In still another variation, as shown in Figure 6, the jacket or apron extension tubing 50 extending upwards opens into the jacket 40 at a higher level, so that the jacket 40 thus becomes a secondary bailed chamber and may be provided with any modification of the automatic and liquid-operated valve means, such as for example the float 30 and downwardly extending tubular conduits 31 of the modification shown in Figure 3.

In practice the various parts, particularly the inlets 11 and the passage between the float 16 and the tubing 8 or between the float 30 and the jacket or apron 40, should be so dimensioned that in each cycle after the liquid has passed by the float, the float will descend, opening the valved means communicating to beneath the plunger 10 in the lift tube 8. It is also preferable that the force required for overcoming the resistance against flow of gas through the inlets 11 should exceed the force required for overcoming the resistance against flow of gas through the opening of the valve means and lifting the plunger.

In all the modifications of the invention thus far described use is made of mechanical means for temporarily shutting off the space in the lift tube below the plunger. If, however, the velocity of the pressure gas entering the accumulating space, i. e. the rate of pressure increase of said gas, is kept within certain limits, these mechanical means may be dispensed with.

This may be explained, for example with reference to the embodiment according to Figure 7, which, in fact, is the same as that according to Figure 3, after removal of valve 13 with seat 12 and float 30 with guides 32.

It is clear that the plunger will be lifted only when the difference between the pressures against the bottom of the plunger and at the top thereof respectively becomes larger than that equal to the plunger weight or, in other words, when the force which it is necessary to overcome to convey the fluid from point 33 to point 11 through conduit 31 is greater than the force which it is necessary to overcome to convey the same fluid from point 33 to point 11 through port 20, thereby lifting the plunger.

This means that, as long as the liquid level in the accumulating space stands above opening 20, lifting will take place only when the pressure loss between the above-mentioned points due to resistance to flow of liquid of said conduit is larger than that equal to the weight of the plunger less its liquid displacement. This resistance may be kept low by keeping the rate of pressure gas supply within moderate limits, so that the plunger will stay at rest.

The total resistance to flow through the conduit 31 is equal to friction resistance plus the hydrostatic head, the latter having a zero value when the conduit 31 is totally submerged in the fluid in chamber 5. As the fluid level in chamber 5 recedes, however, the hydrostatic head in conduit 31 increases in value, therefore, while the fluid level in chamber 5 recedes from point 11 to point 33. The increasing resistance to flow through conduit 31 builds up, therefore, when the fluid in chamber 5 has receded to a predetermined level below point 20, to a value greater than the resistance to flow of the alternate path 33-20-11, thereby causing the plunger 10 to be lifted.

In the modification shown in Figure 2 the mechanical means 22-28 may be dispensed with as well, the only conditions for satisfactory operation then being that the upwardly directed pipe 21 is extended to a predetermined height above the inlet ports 11, as shown in Figure 8, and that the resistance to flow of liquid through inlet ports 11 is kept within certain limits.

The liquid level in the accumulating space once being depressed below opening 34, the liquid head inside pipe 21, which remains constant, will no longer be balanced by that outside said pipe and a hydrostatic head of a value which continuously increases as the level in chamber 5 is depressed will be applied upwards to the lower face of plunger 10. The plunger 10 will therefore be lifted as soon as the following inequality of forces obtains in the apparatus of Fig. 8.

$$F_{11} + H_{21} - F_{21} > W_{10} + F_{10}$$

wherein

F_{11} is the force of friction opposing fluid flow through ports 11

H_{21} is the hydrostatic head of the fluid column in conduit 21

F_{21} is the force of friction opposing fluid flow in conduit 21

W_{10} is the weight of plunger 10

F_{10} is the force of friction opposing the motion of plunger 10

It will be understood that it is also possible to combine the modifications of Figures 7 and 8, the device then showing a conduit extending downwards from inlet ports 11 and another conduit extending upwards from inlet port 20, the opening 34 of the latter conduit then lying at a predetermined distance above the opening 33 of the former conduit.

As mentioned above, the modifications according to Figures 7 and 8 are rather sensitive as regards the rate at which the pressure gas is to be admitted into the accumulating space, the resistance to flow of liquid into the space in the lift tube above the plunger being an important factor.

This difficulty may be overcome if in the way of both the passages to the spaces in the lift tube above and below the plunger respectively choke means are inserted for neutralizing the effect of too fast a pressure gas admittance on the liquid flow, which is illustrated in Figure 9, showing a compartment 35, an inlet port or passage 20 to the space below the plunger, a conduit or passage means 31 from said compartment to the inlet ports 11 above the plunger and a passage 36 between the accumulating chamber and said compartment. Choking may be attained, for instance, by so dimensioning the passage 36 and passage means 31 that the resistance to flow of liquid of the former is larger than that of the latter or by providing said passage 36 with a downwardly extending pipe in the manner of tubing 60 in Figure 6.

It is to be understood that many other variations may be made without departing from the spirit of the present invention. For example, there may be provided one or more passages between the accumulating space and the spaces in the lift tube above and below the plunger. Or, for instance, suitable shock absorbers may be provided at each end of the stroke of the plunger. Or the inner casing 4 may be omitted entirely by providing the holes 3 in the well casing 2 with inwardly opening one-way valves, whereby the lower portion of the casing becomes the bailer chamber and the annular space between the tubing 8 and the casing 2 becomes the conduit for high pressure gas. Or various types of guiding means may be used with the moving parts to ensure proper alignment.

I claim as my invention:

1. In a gas-lift system, the combination of a tubular string extending into a well, the lower portion of said string forming a liquid-accumulating chamber, said chamber having a non-return inlet valve, means for delivering pressure gas to said chamber, a lift tube depending into said chamber, a plunger freely movable in said tube, means to support said plunger at rest adjacent to the lower end of said tube within said chamber, upper inlet ports above the plunger at rest in said tube to permit liquid accumulation in said tube above said plunger, a lower inlet port connecting said tube below the plunger at rest therein with said chamber and level-responsive means for controlling flow through said upper and lower inlet ports.

2. In a gas-lift system, the combination of a tubular string extending into a well, the lower portion of said string forming a liquid-accumulating chamber, said chamber having a non-return inlet valve, means for delivering pressure gas to said chamber, a lift tube depending into said chamber, inlet ports in said tube adjacent to the lower end thereof within said chamber,

5 a plunger freely movable in said tube, means to support said plunger at rest below said ports to permit liquid accumulation in said tube above said plunger, a valve between said chamber and said tube below the plunger at rest in said tube, and level-responsive means within said chamber adapted to open said valve when the pressure gas admitted into said chamber depresses the liquid therein to a predetermined level.

10 3. In a gas-lift system, the combination of a tubular string extending into a well, the lower portion of said string forming a liquid-accumulating chamber, said chamber having a non-return inlet valve, means for delivering pressure gas to said chamber, a lift tube depending into said chamber, inlet ports in said tube adjacent to the lower end thereof within said chamber, a plunger freely movable in said tube, means to support said plunger at rest below said ports to permit liquid accumulation in said tube above said plunger, a valve between said chamber and said tube below the plunger at rest in said tube, said valve comprising a stationary valve seat member and a movable valve member normally held in closed position against said seat member by resilient means, and floatable means adapted to act against said resilient means and to force said movable valve member away from said stationary seat member when the pressure gas admitted into said chamber depresses the liquid therein to a predetermined level.

15 4. In a gas-lift system, the combination of a tubular string extending into a well, the lower portion of said string forming a liquid-accumulating chamber, said chamber having a non-return inlet valve, means for delivering pressure gas to said chamber, a lift tube depending into said chamber, inlet ports in said tube adjacent to the lower end thereof within said chamber, a plunger freely movable in said tube, means to support said plunger at rest below said ports to permit liquid accumulation in said tube above said plunger, a valve between said chamber and said tube below the plunger at rest in said tube, said valve comprising a stationary valve seat member and a movable valve member carried by floatable means adapted to open said valve when the pressure gas admitted into said chamber depresses the liquid therein to a predetermined level.

20 5. In a gas-lift system, the combination of a tubular string extending into a well, the lower portion of said string forming a liquid-accumulating chamber, said chamber having a non-return inlet valve, means for delivering pressure gas to said chamber, a lift tube depending into said chamber, inlet ports in said tube adjacent to the lower end thereof within said chamber, conduits attached to said tube about said inlet ports, said conduits extending downwards toward and opening to the lower portion of said chamber, a plunger freely movable in said tube, means to support said plunger at rest below said ports to permit liquid accumulation in said tube above said plunger, a valve between said chamber and said tube below the plunger at rest in said tube, and level-responsive means within said chamber adapted to open said valve when the pressure gas admitted into said chamber depresses the liquid therein to a predetermined level.

25 6. In a gas-lift system, the combination of a tubular string extending into a well, the lower portion of said string forming a liquid-accumulating chamber, said chamber having a non-return inlet valve, means for delivering pressure

gas to said chamber, a lift tube depending into said chamber, a plunger freely movable in said tube, means to support said plunger at rest adjacent to the lower end of said tube within said chamber, upper inlet ports above the plunger at rest in said tube to permit liquid accumulation in said tube above said plunger, a lower inlet port connecting said tube below the plunger at rest therein with said chamber and level-responsive means for controlling flow through said upper and lower inlet ports, said flow control means consisting of conduits attached to said tube about said upper inlet ports and extending downwards within said chamber for opening below said lower inlet port.

7. In a gas-lift system, the combination of a tubular string extending into a well, the lower portion of said string forming a liquid-accumu-

lating chamber, said chamber having a non-return inlet valve, means for delivering pressure gas to said chamber, a lift tube depending into said chamber, a plunger freely movable in said tube, means to support said plunger at rest adjacent to the lower end of said tube within said chamber, upper inlet ports above the plunger at rest in said tube to permit liquid accumulation in said tube above said plunger, a lower inlet port connecting said tube below the plunger at rest therein with said chamber and level-responsive means for controlling flow through said upper and lower inlet ports, said flow control means comprising an upwardly-extending conduit attached to said tube about said lower inlet port, said conduit having an opening above said upper inlet ports.

ALEXANDER WILHELMUS STEENBERGH.
